HORACE H. BURDETT, OF HOPEDALE, MASSACHUSETTS, ASSIGNOR TO DRAPER CORPORATION, OF HOPEDALE, MASSACHUSETTS, A CORPORATION OF MAINE.

BUILDER MECHANISM FOR YARN-WINDING MACHINES.

Application filed May 1, 1925. Serial No. 27,177.

To all whom it may concern:

Be it known that I, HORACE H. BURDETT, a citizen of the United States, and a resident of Hopedale, in the county of Worcester and State of Massachusetts, have invented an Improvement in Builder Mechanism for Yarn-Winding Machines, of which the following description, in connection with the accompanying drawings, is a specification, like characters on the drawings representing like parts.

This invention relates to builder mechanisms for yarn winding or spinning machines.

In that type of looms known as "feeler looms" it is now the common practice to wind filling carriers or bobbins for use in such looms by providing a few preliminary windings upon the filling carriers or bobbins, technically now known as a "bunch," and upon the completion of such preliminary windings or bunch to pass to the regular service windings, and various types of mechanisms have been devised for this purpose. One of the objects of the present invention is to provide a builder mechanism with a bunch building attachment of simple and novel character which is readily applicable to builder mechanisms now in common use and which has for its purpose to lay upon the filling carriers or bobbins the preliminary windings or bunch and then to automatically pass to the regular service windings when the bunch has been completed. When such wound filling carriers or bobbins are employed in "feeler looms" the preliminary windings or bunch insure that a complete shot of filling shall be laid in the shed on the last pick of the shuttle prior to filling replenishment.

When the builder mechanism passes from the bunch to regular service windings, it is desirable that the builder arm and perforce the connected yarn guides, such as a ring rail, for instance, will not "jump," and another important feature of the present invention consists in means associated with the bunch building elements for preventing such jump.

In winding successive yarn carriers or bobbins it is important that the mass of yarn constituting the preliminary windings or bunch shall be uniform or of the same amount, and another feature of the invention, therefore, consists of means to insure

that the bunch on the successive bobbins or successive series of bobbins shall contain the same amount of yarn. This is important because the yarn in the bunch usually constitutes waste when filling replenishment is effected in the loom, and a predetermined knowledge of the amount of such waste gives data for determining the amount of yarn which shall constitute the bunch in a successive series.

The invention, novel features thereof, and new combination of parts will best be made clear from the following description and the accompanying drawings of one good form of the invention, which in its true scope will be definitely set forth in the claims.

In the drawings:

Fig. 1 is a perspective view of a spinning or winding machine having the present invention associated therewith;

Fig. 2 is a front elevation, with some of the parts shown in section, and illustrating more particularly the relation of the elements during the bunch building operation;

Fig. 3 is an enlarged side elevation of the parts shown in Fig. 2;

Fig. 4 is a similar side elevation to that shown in Fig. 3, but illustrating the relation of parts after the completion of the bunch and during main winding; and

Fig. 5 is a side elevation of a filling carrier or bobbin having the bunch wound thereon.

The advantages of the present invention are well manifested in connection with a spinning machine, and as shown in the present embodiment thereof, the spinning machine is of the "ring" type, but, obviously, the invention is not restricted thereto as it may be advantageously employed in connection with any machine for winding bobbins with filling wind.

In the drawings, the machine frame 1 for supporting the operating parts may be of any usual or well-known type, and, as shown, consists of end frames of usual character connected by a cross-member 2 and a fixed spindle rail 3 on which the filling carriers or bobbins to be supplied with yarn are rotatably mounted. Above the spindle rail 3 is the ring rail 4 of usual construction and having the spinning rings 5 through which the filling carriers or bobbins 6 extend. Secured to the ring rail 4 are the lifter rods 7 which by their up and

down movement effect the traverse of the ring rail to lay the yarn upon the yarn receive 3 or bobbins. As shown, the lifter rods 7, of which there may be any suitable number, have shoes 8 which rest upon the pin or roller 9 upon arms 10 mounted for rocking movement in supporting brackets 11 secured to the machine frame. The arms 10 are secured, in the present instance, to the transverse shaft 12 to which is connected an arm 13 having a weight 14 normally tending to lift the ring rail or yarn guide.

Secured to the rock shaft 12 is the arm 15, usually known as the "segment" arm, which is connected to the builder mechanism, to be hereinafter described, by means of a flexible connection or chain 16, and in order that the various lifter arms 10 may be moved in unison, the rock shafts 12, of which there may be any suitable number, are connected together by a rod 17. The above described mechanism is of the usual type and the details thereof form no essential part of the present invention.

Pivottally mounted on the machine frame at 18 is the builder arm 19, the rearwardly extending tail end of such arm, as at 20, being provided with a counterweight 21 for normally holding the follower 22 against the peripheral portion of the main builder cam 23, which is driven from any suitable source of power, as usual in this general type of builder mechanisms. As shown, the main builder cam is mounted upon a shaft or stud 24 supported by the machine frame.

The builder arm 19 carries the usual let-back drum 25 to which one end of the flexible connection or chain 16 is secured, as at 26, and said drum 25 carries a worm gear 27 which is given a rotative movement to let back on the flexible connection 16 through a worm 28 mounted on the worm shaft 29 and provided with a pick wheel 30, the construction being such that as the builder arm is raised and lowered, the pick wheel 30 is stepped along by the usual pick mechanism 31 to let back on the flexible connection 16. These features may be as usual in builder mechanisms now in common use.

In accordance with the present invention, the builder arm is provided with a worm which is normally under the influence of means for moving the worm transversely relative to the builder arm into bunch building relation with a rotating bunch building device, the construction being such that the worm is restrained from movement to bunch building position during regular windings, by the rotating bunch building device but is permitted to move to bunch building position relative thereto when the builder arm is depressed.

More specifically, the builder arm, in the present instance, is provided with a bracket or support 32 which may be appropriately

secured to the builder arm by pins or bolts 33. In the present instance, the bracket or support 32 is provided with slots 34 through which the pins or bolts 33 extend, and adjusting screws 35 serve to effect proper adjustment of the bracket with respect to the builder arm.

The downwardly extending portion 36 of the bracket, Fig. 2, carries a worm which is normally pressed laterally of the builder arm to impart to the worm a tendency to assume its bunch building position. In the present instance, the pin 37 is secured to the lower extending portion 36 of the bracket and is provided with screw threads 38, whereby the pin 37 may be adjusted laterally of the builder arm by means of an adjusting nut 39 or other suitable adjusting means.

The pin 37 has the enlarged or shoulder portion 40 on which is mounted a worm 41, the hub portion 42 of which embraces the enlarged portion 40 of the pin and has a limiting shoulder 43. Between the inner face of the worm and the bracket arm 36 is interposed a spring 44 normally tending to move the worm 41 laterally of the builder arm into bunch building position relative to the rotary bunch builder device.

The rotary bunch builder device may be mounted for rotating movement through any suitable connections, but as shown in the present instance of the invention, the rotary bunch builder device 45 is constituted as a disk and is secured by bolts 46 to the main builder cam 23, suitable shoulders 47 being interposed between the rotary bunch builder device 45 and the outer face of the bunch builder cam. The rotary bunch builder device has a peripheral edge portion 48 adapted to travel in the grooves of the worm 41, with the result that when the parts are in bunch building position, as indicated in Fig. 2, the worm will be rotated by the rotary bunch builder device and be moved laterally relative to the builder arm against the tension of the spring 44, until when the worm 41 has been moved sufficiently far to traverse the worm out of operative relation with the rotary bunch builder device, the bunch will have been completed.

From the construction thus far described, it will be apparent that the builder arm has mounted thereon a bunch building member or worm 41 which is normally under the influence of the spring 44 tending to move it laterally from the builder arm into bunch building position for cooperation with the rotating bunch building device 45, and when the builder arm 19 is depressed, the spring 44 acts at once to project or move the worm 41 into bunch building position, as indicated in Fig. 2.

During main service windings, it is nec-

essary that the bunch builder worm be held from movement into bunch building position, and such movement is prevented during main traverse windings by engagement 5 of the outer face of the worm 41 with the side of the rotary bunch builder device 45.

When a series of filling carriers or bobbins have been fully wound and are to be "doffed", it is usual to depress the ring rail 10 for doffing, the winding machine at such times being at rest or stopped. When a fresh unwound series of filling carriers or bobbins have been supplied to the machine and the latter is ready for commencing to 15 wind a new series of filling carriers or bobbins, the machine attendant will depress the builder arm, thereby carrying downwardly the worm 41 from the position shown in Fig. 4 where the outer face of the worm bears 20 against the side of the rotary bunch builder device, and the spring 44 will at once move the worm outwardly into bunch building relation with the rotary bunch builder device 45, so that on letting up the bunch builder 25 arm the machine will be set to commence the preliminary or bunch windings. As the rotary bunch builder device 45 rotates during the bunch building operation, as indicated in Fig. 2, the worm 41 will be rotated to 30 move it backwardly against the normal action of the spring 44, until when the end of the worm is presented to the rotary bunch builder device 45, the builder arm will rise from the action of the counterweight 41 and 35 ring rail to cause the outer face of the worm to bear against the side of the rotary bunch builder device 45, and the follower 42 will come into engagement with the regular builder cam, whereupon the windings of the 40 filling carriers or bobbins will be continued with regular service wind.

The amount of yarn to be contained in the preliminary windings or bunch will be determined by the extent of movement of 45 the worm 41 outwardly into bunch building position when the builder arm 19 is depressed, and the amount of such movement may be conveniently regulated or determined by adjustment of the nut 39 on the threaded portion 38 of the pin 37 which carries the worm 41.

In passing from bunch building to regular service wind, it is desirable that the builder arm and perforce the connected yarn guides or ring rail shall not "jump," and to effect a gradual approach of the follower 55 22 into contact with the periphery of the main builder cam as the worm 41 is moved outwardly and finally leaves the edge of the 60 rotary bunch builder device 45, the outer face portion of the worm 41 is provided with a scroll track 49 of gradually decreasing radius, as indicated in Figs. 1, 3 and 4, with the result that as the worm is moved outwardly from its bunch building position,

the rotary bunch builder device will permit the builder arm to gradually rise until the follower 22 takes upon the peripheral portion of the main builder cam. Thus, all objectionable shock or jump in passing from 70 the bunch builder wind to the main builder wind is avoided.

Since the worm 41 is rotatable under the action of the rotary bunch builder device 45, it follows that when the outer face 50 75 of the worm bears upon the side of the rotary bunch builder device during regular service wind, that the worm 41 is liable to turn under the frictional engagement with the rotary bunch builder device. The effect 80 of this would be to cause the worm to present variable circumferential portions of the worm groove to the rotary bunch builder device when, upon depression of the builder arm, the worm is moved into bunch building position, and in accordance with the present invention means are provided to prevent such variation of engagement between the worm and the rotary bunch building 85 device.

A simple form of means to this end consists of a pin 51 which, should the worm be rotated by the rotary bunch builder device during main service wind, would engage the peripheral portion of the bunch builder device and arrest or stop further movement, and since the pin or stop 51 is located to come into action on the completion of a bunch, it insures that at the commencement 90 of the next bunch wound, the worm 41 will 100 have the same peripheral portion of its groove presented to the rotary bunch builder device and that the bunches on the new set of bobbins will be commenced at the same point of the worm where the previously wound bunches had commenced.

The invention, therefore, provides a simple construction of bunch building attachment which may be associated with the usual builder mechanisms now in use to effect, first, the winding of uniform bunches of successive series of bobbins or filling carriers which shall be of the same size and amount of filling, and second, obviate the undesirable jump by passing from bunch building to regular service wind at the completion of the bunch. It also insures that bunches successively wound on a series of filling carriers or bobbins shall commence at the same point of the worm at which other bunches or preliminary windings have commenced.

In the illustrated form of the invention, the rotary bunch builder device is in the form of a disk which is found to be a good, 110 practical feature, and consequently little or no traverse is given to the yarn during the bunch building operation, but, if desired, the rotary bunch builder device may be otherwise formed, with a somewhat irregular 115 120 125 130

surface to give any desired traverse to the yarn during the bunch building operation. In any event, however, it is desirable that when the bunch is completed and the machine passes to the regular service wind, that the traverse of the regular wind shall not pass below or towards the head of the bobbin beyond about the central portion of the bunch, as otherwise the yarn may be broken as the unwindings thereof approach the bunch windings. The filling carrier or bobbin, as illustrated in Fig. 5, has the bunch 53 wound thereon in accordance with the present disclosure of the invention, and the regular windings 54, as will be observed, pass downwardly to about the central portion of the bunch, but preferably do not go below the bunch, and while the bunch is preferably indicated as being laid upon the bobbin near the head thereof, this is not always necessary since the bunch may be positioned at various portions of the filling carrier, but the location of the bunch near the head of the bobbin is preferable because breakage of the yarn as it is withdrawn from the bobbin is avoided in accordance with the present embodiment of the invention.

What is claimed is:

- 30 1. In a builder mechanism, the combination of a main builder cam, a builder arm, a bunch building member mounted on the builder arm, means normally tending to move said member transversely of said arm into bunch building position, a bunch building device rotating with the main builder cam and acting to restrain the said member from such movement during main traverse winds until the builder arm is depressed and thereupon permitting said member to be moved by said normally acting means into bunch building relation with the bunch building device.
- 45 2. In a builder mechanism, the combination of a main builder cam, a builder arm, a bunch building member mounted on the builder arm, means normally tending to move said member transversely of said arm into bunch building position, a rotating bunch building device of larger diameter than the main builder cam acting to restrain such movement of the bunch building member during main traverse wind until the builder cam is depressed and thereupon permitting said member to be moved by the normally acting means into bunch building relation with the bunch building device.
- 55 3. In a builder mechanism, the combination of a builder cam, a builder arm, a bunch building member mounted on the builder arm and having a worm, means normally tending to move said member transversely of said arm, a rotating bunch builder device acting normally to restrain movement of said member until the builder arm is depressed and thereupon permitting the worm to engage the rotating device to build the bunch.
- 60 4. In a builder mechanism, the combination of a main builder cam, a builder arm, a bunch building member mounted on the builder arm and having a worm, a rotating device to cooperate with said worm to build the bunch and upon completion thereof to permit main service traverse, a spring normally acting upon said member and holding it against the side of the rotating device during the main traverse and to move the worm into cooperative relation with the rotating device when the builder arm is depressed.
- 65 5. In a builder mechanism, the combination of a main builder cam, a builder arm, a rotating bunch builder device of larger diameter than the main builder cam, a bunch builder member on the builder arm, means normally tending to move the said member transversely of the builder arm and restrained from effecting such movement by the rotating bunch builder device during service traverse until the builder arm is depressed that the member on the builder arm may then move into bunch building relation with the rotating bunch building device.
- 70 6. In a builder mechanism, the combination of a main builder cam, a builder arm, a rotating bunch builder device of larger diameter than the main builder cam, a bunch builder member on the builder arm, means normally tending to move the said member transversely of the builder arm and restrained from effecting such movement by the rotating bunch builder device during service traverse until the builder arm is depressed that the member on the builder arm may then move into bunch building relation with the rotating bunch building device, and means rendered effective by the bunch builder device to move the bunch builder member out of cooperative relation therewith against the normally acting means.
- 75 7. In a builder mechanism, the combination of a main builder cam, a builder arm, a rotating bunch builder device of larger diameter than the main builder cam, a bunch builder member on the builder arm, means normally tending to move the said member transversely of the builder arm and restrained from effecting such movement by the rotating bunch builder device during service traverse until the builder arm is depressed that the member on the builder arm may then move into bunch building relation with the rotating bunch building device, and means for varying the extent of movement of the bunch builder member under the normally acting means.
- 80 8. In a builder mechanism, the combination of a main builder cam, a builder arm, a rotating bunch builder device of larger diameter than the main builder cam, a bunch builder member on the builder arm, means normally tending to move the said member transversely of the builder arm and restrained from effecting such movement by the rotating bunch builder device during service traverse until the builder arm is depressed that the member on the builder arm may then move into bunch building relation with the rotating bunch building device, and means for varying the extent of movement of the bunch builder member under the normally acting means.

tion of a main builder cam, a builder arm having a follower engaged by the main builder cam during service winding, a pin on the builder arm carrying a worm, means 5 tending normally to move the worm laterally of the builder arm into bunch building position, a rotating bunch builder disk-like member for cooperation with the worm to build a bunch and acting during main service 10 ice traverse to restrain movement of the worm to bunch building position until the builder arm is depressed.

9. In a builder mechanism, a main builder cam, a builder arm, a pin on the builder arm 15 carrying a worm, means normally tending to move the worm laterally of the arm to a predetermined extent, a rotating device for cooperation with the worm during the bunch building operation and for moving the worm 20 transversely of the builder arm against said normally acting means to complete the bunch and thereupon acting to restrain movement of the worm to bunch building position during main service windings.

25 10. In a builder mechanism, a main builder cam, a builder arm, a pin on the builder arm carrying a worm, means normally tending to move the worm laterally of the arm to a predetermined extent, means for varying 30 the predetermined extent of such movement to vary the size of the bunch, a rotating device for cooperation with the worm during the bunch building operation and for moving the worm transversely of the builder arm 35 against said normally acting means to complete the bunch and thereupon acting to restrain movement of the worm to bunch building position during main service windings.

40 11. In a builder mechanism, the combination of a main builder cam, a builder arm having a follower for engagement with said cam during main service windings, a rotating bunch builder device, a worm carried by the 45 builder arm for cooperation with said device in building the bunch and moved by the rotating device out of bunch building position on completion of the bunch, and means for avoiding jump of the builder arm on 50 passing from bunch to regular service windings.

55 12. In a builder mechanism, the combination of a main builder cam, a builder arm having a follower for engagement with said cam during main service windings, a rotating bunch builder device, a worm carried by the 60 builder arm for cooperation with said device in building the bunch and moved by the rotating device out of bunch building position on completion of the bunch, and a scroll of gradually decreasing radius for avoiding jump of the builder cam on passing from bunch to regular service windings.

65 13. In a builder mechanism, the combination of a main builder cam, a builder arm

having a follower for engagement with said cam during main service windings, a rotating bunch builder device, a worm carried by the builder arm for cooperation with said device in building the bunch and moved by the rotating device out of bunch building position on completion of the bunch and a scroll of gradually decreasing radius at the end of the worm for avoiding jump in passing from bunch to regular service windings. 75

14. In a builder mechanism, the combination of a main builder cam, a builder arm having a follower for engagement with said cam during main service windings, a rotating bunch builder device, a worm carried by the builder arm for cooperation with said device in building the bunch and moved by the rotating device out of bunch building position on completion of the bunch, means normally acting to move the worm into bunch building position and restrained by the rotary bunch building device during regular service windings until the builder arm is depressed, and means for preventing jump of the builder arm on passing from bunch to regular service windings. 80

15. In a builder mechanism, the combination of a main builder cam, a builder arm having a follower for engagement with said cam during main service windings, a rotating bunch builder device, a worm carried by the builder arm for cooperation with said device in building the bunch and moved by the rotating device out of bunch building position on completion of the bunch, a stop 95 for determining the rotative position of the worm during regular service windings that successive bunches may start at the same part of the worm. 100

16. In a builder mechanism, the combination of a main builder cam, a builder arm having a follower for engagement with said cam during main service windings, a rotating bunch builder device, a worm carried by the builder arm for cooperation with said device in building the bunch and moved by the rotating device out of bunch building position on completion of the bunch, a scroll of gradually decreasing radius for avoiding jump of the builder arm on passing from bunch to regular service windings, and a stop for determining the rotative position of the worm that successive bunches may start at the same part of the worm. 105

17. In a builder mechanism, the combination of a main builder cam, a builder arm having a cam follower, a rotating disk like bunch builder device, a worm carried by the builder arm, means normally acting to move the worm into bunch building position and restrained from effecting such movement by engagement with the side of the disk like bunch building device until the builder arm is depressed, and means for varying the extent of movement of the worm under the 110 115 120 125 130

normally acting means to vary the size of the bunch.

18. In a builder mechanism, the combination of a main builder cam, a builder arm having a cam follower, a rotating disk-like bunch builder device, a worm carried by the builder arm, means normally acting to move the worm into bunch building position and restrained from effecting such movement by engagement with the side of the disk-like bunch building device until the builder arm is depressed, means for varying the extent of movement of the worm under the normally acting means to vary the size of the bunch, and means for determining the rotative position of the worm at the completion of a bunch that successive bunches may be of the same size.

19. In a builder mechanism, the combination of a main builder cam, a builder arm having a cam follower, a rotating bunch building disk, a worm on the builder arm, a spring acting normally to move the worm into bunch building position relative to the rotating disk and held from effecting such movement by engaging the side of the disk during regular traverse windings until the builder arm is depressed, an adjusting device for determining the amount of such move-

ment of the worm when the builder arm is depressed to regulate the size of the bunch, and means for determining the rotative position of the worm on the completion of a bunch that successive bunches of the same size may be wound.

20. In a builder mechanism, the combination of a main builder cam, a builder arm having a cam follower, a rotating bunch building disk, a worm on the builder arm, a spring acting normally to move the worm into bunch building position relative to the rotating disk and held from effecting such movement by engaging the side of the disk during regular traverse windings until the builder arm is depressed, an adjusting device for determining the amount of such movement of the worm when the builder arm is depressed to regulate the size of the bunch, means for determining the rotative position of the worm on the completion of a bunch that successive bunches of the same size may be wound, and means between the worm and rotating disk for preventing jump when passing from bunch to regular service windings.

In testimony whereof I have signed my name to this specification.

HORACE H. BURDETT.
